UNITED STATES PATENT OFFICE.

Serial No. 401,301, filed April 1, 1919, and of which a copy is filed herewith.

INVENTOR, NAGAKATA NISHI AND NAGASUMI NISHI, OF BERKELEY, CALIFORNIA.

IMPROVEMENT IN A THERMAL CIRCUIT-CONTROLLER.

Entitled "An Improvement in Thermal Circuit-Controller," Serial No. 270,728, filed January 11, 1919, and of which a copy is filed herewith.

1,377,848. Specification of Letters Patent. Patented May 10, 1921.

Application filed July 5, 1919. Serial No. 308,783.

To all whom it may concern:

Be it known that we, NAGAKATA NISHI and NAGASUMI NISHI, subjects of the Emperor of Japan, residing at Berkeley, in the county of Alameda and State of California, have invented certain new and useful Improvements in Thermal Circuit-Controllers, of which the following is a specification.

Our invention is a thermal circuit controller, and is an improvement over our invention disclosed in our application filed January 11, 1919, Serial No. 270,728.

Referring to the annexed drawings which form a part of this specification—

Figure 1 is a vertical longitudinal section of our invention and an electric iron to which it is applied, taken on line 1—1 of Fig. 3.

Fig. 2 is a rear view of our invention as shown in Fig. 1 partly in section.

Fig. 3 is a horizontal sectional view of our invention taken on line 3—3 of Fig. 1.

Fig. 4 is an enlarged sectional view taken on line 4—4 of Fig. 2.

Fig. 5 is a perspective view of a unit of our invention.

Fig. 6 is a bottom plan of the iron heating element.

Fig. 7 is a top plan of the iron heating element.

Fig. 8 is a side view partly in cross-section of the unit shown in Fig. 5.

Fig. 9 is a fragmentary section taken on line 9—9 of Fig. 3.

Fig. 10 is a plan of one of the connecting clips.

In the drawings 1 indicates the base of an electric iron formed with a lower ironing surface 2. A pair of upstanding studs 3 and 4 are screwed into the top of the base 1 on the central axis thereof. On the top of the base rests a plate of mica 5, the studs 3 and 4 extending through apertures 6 and 7 in said plate. On said mica plate rests a heating element 10 which includes a pair of flat heating coils 11 and 12 wound on mica plates 13 and 14, a plate of mica 15 covering said heating coils, and a pair of metal conductor plates 16 and 17 resting on plate 15 directly over said heating coils; the studs 3 and 4 projecting through apertures 18 and 19 in plate 15 and between the heating coils 11 and 12 and between the plates 16 and 17. The heating coils 11 and 12 and plates 16 and 17 are secured upon the plate 15 by rivets 20 and 21, the rivet

20 holding the heating coil 11 and plate 16 to the plate 15, and the rivet 21 holding heating coil 13 and plate 17 to plate 15. A plate 23 of mica rests upon plates 16 and 17 of the heating element 10, the studs 3 and 4 extending through apertures 24 and 25 in the plates. A thick metal plate 26 provided with apertures 27 and 28 rests upon the mica plate 23, the studs 2 and 3 extending through said apertures. Nuts 29 and 30 screw on the upper ends of the stud bases against the top plate 26 and clamp the heating element 10 and mica plates 5 and 23 between the plate 26 and base 1. The upper portions of the studs 3 and 4 are reduced and threaded. A cover 35 provided with apertures 36 and 37 fits upon the base 1 over the heating element 10 and plates 5, 23 and 26 and nuts 29 and 30, the reduced upper portions of studs 3 and 4 extending through said apertures 36 and 37. Nuts 38 screw on the threaded reduced portions of the studs 3 and 4 against the top of the cover 35 and clamp said cover in position on the base 1 and over the parts as described. A handle bracket 40 provided with apertures 41 and 42 rests upon nuts 38 and 39, the studs 3 and 4 projecting through said apertures, and nuts 43 and 44 screw on the ends of said studs against the bracket and clamp the bracket in position. A handle 45 is secured to the upper ends of bracket 40.

A stud 50 of copper or other suitable material of the proper coefficient of expansion, heat conductivity, melting point and specific heat, is welded or otherwise secured to the top of the base 1 at the rear thereof and projects upwardly into a recess 51 formed in the upper rear part of cover 35 through an opening 52 at the bottom of said recess in said cover. A unitary member 55 of my circuit controller, including a base 56 and studs 57 and 58, is secured to the top of the base 1 at the rear thereof by means of screws 59 extending through apertures 60 in base 56 and screwing into base 1, a spring washer 61 and a washer 62 being interposed between the base 56 and the head of each of said screws. The base 56 is curved rearwardly between the studs 57 and 58 to fit rearwardly around the stud 50 so that the studs 57 and 58 stand up respectively at the sides of stud 50 through opening 52 and recess 51. The base 56 and the studs 57 and 58 are made of porcelain or other

suitable insulating material which will not expand or contract under the influence of the temperature of the iron base 1. A metal cap 63 fits over the top of the stud 57 and rests upon a shoulder 64 on said stud, and is detachably secured to said stud by a bolt 65, extending through the cap and the stud, and a nut 66 screwing on the end of said bolt against the cap. Ears 67 are formed on the lower part of cap 63 between which fits one end of a contact arm 68 of insulating material which is pivoted to said ears by a pivot 69. A clip 70 fits over the top of the stud 58. Said clip is H-shaped, comprising vertical front and rear walls 71 and an intermediate wall 72 extending horizontally between and connecting said vertical walls. The vertical walls 71 below the wall 72 fit over the front and rear sides of stud 58 and rest upon shoulders 73 in said stud, while the wall 72 rests upon the top of the stud. The clip 70 is detachably secured to the stud 58 by a bolt 74 extending through walls 71 and the stud and a nut 75 screwing on the end of said bolt against one of the walls 71. The swinging end of arm 68 swings between the upper portion of walls 71. In the top of cap 63 is formed a socket 76. On the upper face of wall 72 of clip 70 is a contact 79 adapted to be engaged by a contact 80 on the bottom of the swinging end of arm 68. The contact 80 is formed on the head of a screw 81 extending through the bottom of arm 68 and screwing into a contact 82 in the bottom of a socket 83 formed in the top of the swinging end of the arm 68. A threaded shank 85 extends vertically from the top of stud 50 and an internally threaded sleeve 86 screws on said stud. The sleeve 86 is also externally threaded and an internally threaded cap 87 screws on the sleeve 86. The cap 87 has a conical top 88 for engaging the under side of arm 68. A stud 90 projects radially from the lower edge of sleeve 86, on which stud an indicator 91 telescopes. A plate 95 is secured to the rear end of cover 35 by screws 95' from the upper end of which plates a dial 96 extends rearwardly in a horizontal direction. The plate 95 is provided with a horizontal slot 97 and the dial 96 is provided with an arcuate slot 98 concentric with the axis of the sleeve 86, through which slots extends the indicator 91, pointing to a scale 100 on the dial 96.

The scale 100 is a novel feature of our invention. The extreme right of slot 98 is marked Off, to which the indicator 91 points to indicate that the electric current passing through the iron is turned off. Slightly to the left of character Off is a mark denoted On, to which the indicator 91 points to indicate that the current at this point is turned on. To the left of character

On are marks 101, 102, 103, 104 and 105 and between said marks are intermediate graduating marks 106. The marks 101, 103 and 105 extend rearwardly beyond marks 106 and are connected with an arc 107 described from the center of sleeve 86. The lines 102 and 104 extend rearwardly beyond the arc 107 and are connected by an arc 108 described also from the center of sleeve 86. The intersections of the arc 107 and marks 101, 103 and 105, and the intersections of the marks 102 and 104 are prominently indicated. The graduations from mark 101 to mark 103, which are inclosed by a portion of arc 107, determine a heat zone indicated, Silk, within which zone of heat, silk may be ironed with the iron, and at the highest point mark 103, of said zone, the current of the iron when the iron reaches a temperature corresponding to said mark 85 will be automatically turned off, when the indicator points to said mark, to prevent burning of the silk, as will be more fully described. The graduations from mark 102 to mark 104, which are inclosed by the arc 108, determine a heat zone indicated, Wool within which zone, wool may be ironed, and at the highest point of said zone, namely mark 104, the current when the iron reaches a temperature corresponding to said mark 95 will be automatically turned off, if the indicator points to said mark, to prevent burning of the wool. The graduations from mark 103 to mark 105, which are inclosed by the left portion of arc 107, determine a heat zone denoted, Cotton, within which zone, cotton may be ironed, and at the highest point of said zone, namely, mark 105, the current when the iron reaches a temperature corresponding to said mark will be 105 automatically turned off, if the indicator points to said mark, to prevent burning of the cotton. The word Low is marked on the scale to the left of the character On, which indicates, when the indicator is opposite it, 110 that the current and heat of the iron are low. The word High is marked on the scale opposite the mark 105, which indicates, when the indicator points to it, that the current and heat of the iron are high. 115

A block of insulation 110, formed with a recess 111 extending from the bottom thereof, rests in the iron cover recess 51 against the back of handle bracket 40 and against the plate 95, over the unit 55, the stud 50 and the parts mounted thereon, said unit, 120 stud and parts projecting in said recess. Recesses 112 and 113 and conduits 114, 115, 116 and 117 are also formed in the block 110, the conduits leading from the recesses 125 112 and 113 respectively into the recess 111, and the conduits 115 and 116 leading respectively from recesses 112 and 113 out through the top of said block. Clips 118 and 119 fit in the recesses 112 and 113 respectively, 130

which clips each comprise a U-shaped member 120, a member 121, and a screw 122 connecting said members. Springs 123 and 124 are connected at their upper ends to the 5 screws 122 of clips 118 and 119 respectively and extend through conduits 114 and 115 respectively. Contacts 125 and 126 are respectively secured to the lower ends of springs 123 and 124 and fit in sockets 76 and 83 respectively against the bottom of socket 76 and contact 82 in said socket 83. The ends 10 of leads 127 and 128 are respectively connected at their ends to the screws 122 of clips 118 and 119 respectively and extend through conduits 115 and 116 respectively. The block 110 is made in two sections, a front section 130 and a rear section 131, part of the recesses 111, 112 and 113 and the 15 conduits 114, 115, 116 and 117 being formed in section 130 and the other part of said recesses and conduits being formed in section 131. A housing 135 fits over the top of block 110. A bolt 136 extends through the 20 rear wall of housing 135, block sections 131 and 130, front wall of said housing and rear member of handle bracket 40 and a nut 137 screws on the end of said bolt against said bracket whereby the block 110 is detachably secured on the rear of the iron in cover 25 recess 51. The lower edge of the rear wall of the body section 131 is formed with a notch 140 through which the indicator 91 extends. The upper wall of the housing 135 is formed with an aperture 141 through 30 which the leads 127 and 128 extend twisted together. The lower side edges of the housing 135 is formed with flanges 142 through which extend screws 143 screwing into the iron cover 35, thus firmly securing the block 110 on the iron. The upper end of the rear 35 member of bracket 40 has a rear extension 145 extending rearwardly at a slight downward inclination and then downwardly. The upper part of said extension has an 40 aperture 146 through which extend the twisted leads 127 and 128. Said leads are clamped to the lower end of extension 145 by a clamp 147 which comprises a clip 148 and a bolt 149 and nut 150, said bolt extending through the lower end of the extension 145, between the wires 127 and 150 through said clip, and said nut screwing on the end of said bolt against said clip and drawing said clip against said extension and 55 said wires. A spring 155 surrounds the wires 127 and 128 above the extension 145 and rests at its lower end upon said extension, said spring preventing breaking of said wires. A wire 160, connected at one 60 end to the bolt 65 and gripped against the cap 63 by a nut 66, extends downward through an eye 161, cast on the lower front part of stud 57, and is connected at its other end to a lug terminal 162, upstanding from the rear end of plate 16, by 65 means of a screw 163. A wire 170 is connected at one end to clip 70 by bolt 74 and nut 75 and at its other end to a lug terminal 171 by means of a screw 172. By means of nuts 66 and 75 or screws 163, 70 or 172 our circuit controller is readily connected or disconnected from the iron. The rear ends of coils 11 and 12 extend through the mica plate 15 and connect to plates 16 and 17 near terminals 162 and 163. The 75 coils 11 and 12 connect at their forward ends.

The operation of our invention is as follows: The indicator 91 is swung until it points 80 to the degree of heat on the scale 100 at which it is desired to shut off the current of the iron automatically and the sleeve 86 is moved up or down on the threaded shank 85 to set the point of the cap 87 the proper 85 distance from the arm 68. As the heat of the iron rises under the influence of the current passing through the coils 11 and 12, the stud 50 expands upwardly until the predetermined degree of heat is reached, whereupon the point of cap 87 engages and swings arm 68, upwardly on its pivot 69, and disengages the contacts 79 and 80 and breaks the iron circuit, thus preventing the iron from burning the goods which it is ironing. 90 The iron then cools and the cap 87 and arm 68 descend with the contraction of stud 50 until the contact 80 again engages contact 79 and reestablishes the circuit and heat of the iron. The location of the stud 50 is 100 such that the point of the cap 87 engages the arm 68 close to the pivot 69 thereof, whereby the contact 80 moves quickly and at a considerable distance away from the contact 79, or quickly into engagement with said 105 contact under the influence of a slight upward or downward movement of the cap 87 as the stud 50 expands or contracts according to the heat of the iron, thus preventing arcing and burning of the contacts. 110

Our circuit controller may be readily assembled upon the iron or taken apart therefrom. By removing the bolt 136 and screws 143 the block 110 and the parts therein may be lifted out of the cover recess 51, the contacts 125 and 126 slipping out of the sockets 76 and 83. The unit 55 may be readily removed from the iron through cover opening 52 upon unscrewing screws 59. The plate 95, dial 96 and indicator 91 may be readily 120 removed from the iron by unscrewing screws 95, the indicator slipping off the stud 90. By turning the cap 87, said cap may be adjusted to function perfectly in accordance with the indicator 91 and scale 100. 125

Having described our invention we claim:

1. In a thermal circuit controller, a base, an expandable and contractible stud mounted on said base, a threaded shank on said stud, a threaded sleeve screwing on 130

- said shank, an indicator on said sleeve, a scale to which said indicator points, a cap screwing on said sleeve, a pivotally mounted arm, a contact, a second contact on said arm for engaging said first contact, said arm being located to be engaged by said cap to swing the arm and disengage said contacts when said stud has expanded under a predetermined degree of heat.
- 10 2. In a thermal circuit controller, a base, a pair of studs mounted on said base, an arm pivoted on one of said studs, a contact on the other stud, a contact on said arm for engaging the contact on said stud, a block 15 of insulation formed with a recess in the bottom thereof to telescope over said studs and arm, a contact on said stud on which said arm is pivoted, a contact mounted in said block for engaging the contact on said stud when the block is telescoped over said studs and arm, a second contact mounted in said block for engaging the contact on said arm when the block is telescoped over said arm and studs, and means for swinging 20 said arm and disengaging the contacts on said arm and stud when the base reaches a predetermined degree of heat.
3. In a thermal circuit controller, a base, a pair of studs on said base, an arm pivoted 25 on one of said studs, a contact on the other stud, a contact on said arm for engaging said stud contact, said stud on which said arm is pivoted having a socket in the top thereof, the swinging end of said arm having a socket formed in the top thereof, a block of insulation formed with a recess in the bottom thereof for telescoping over said studs and said arm, contacts respectively in said sockets, springs mounted in 30 said block, contacts on the outer ends of said springs adapted to fit in said sockets and engage the contacts therein when said block is telescoped over said studs and arm, and means for swinging said arm and disengaging the contacts on said arm and said stud when said base reaches a predetermined degree of heat.
4. In a thermal circuit controller, a base, a pair of studs mounted on said base, a cap 35 on one of said studs, an arm pivoted to said cap, a contact on the other stud, a contact on said arm for engaging said stud contact, said cap having a socket formed therein, a contact in said socket, a block of insulation formed with a recess in the bottom thereof 40 for telescoping over said studs and arm, a spring
- mounted in said block, a contact on the end of said spring for fitting in said socket against the contact therein, when the block is telescoped over said studs and arm, and means for swinging said arm and disengaging the contacts on said arm and said stud when the base reaches a predetermined degree of heat.
5. In a thermal circuit controller, a base, 45 a pair of studs mounted on said base, an arm pivoted on one of said studs, an H-shaped clip fitting over the top of the other stud, a contact on the connecting wall of said clip, a contact on said arm, said arm swinging between the upright walls of said clip so that the contact on the arm will engage the contact on the clip, and means for swinging said arm and disengaging said contacts when the base reaches a predetermined degree of heat.
6. In a thermal circuit controller, a metal base, a casting of insulating material including a base and two studs upstanding from said base, an arm of insulating material pivotally mounted upon one of said studs, a contact on said arm, a contact on said other stud normally engaged by the contact on said arm, an expansible and contractible stud on said metal base, and means on said latter stud for engaging said arm and disengaging said contacts when said latter stud has expanded under a predetermined degree of heat.
7. In a thermal circuit controller, a base adapted to be heated, a pair of studs of insulation mounted on said base, a metal cap on the top of one of said studs provided with a socket to receive a lead plug, an arm of insulation pivoted at one end to said cap, the other end of said arm having a socket to receive a lead plug, a contact on said socket end of said arm extending into said socket and through the lower side of the arm, a clip on the other stud between which the socket end of said arm swings, a contact in said clip adapted to be engaged by the lower end of the contact on said arm, and expansible and contractible stud on said base, and means on said stud for engaging said arm and disengaging said contacts when said stud has expanded under a predetermined degree of heat.
- In testimony whereof we hereunto affix our signatures.

NAGAKATA NISHI,
NAGASUMI NISHI.
